(57) **CLAIM**

We claim the ornamental design for an integrated light and visor control for an automobile, as shown and described.

DESCRIPTION

FIG. 1 is a bottom perspective view of an integrated light and visor control showing our new design;

FIG. 2 is a left side view of the integrated light and visor control from FIG. 1;

FIG. 3 is a rear view of the integrated light and visor control from FIG. 1;

FIG. 4 is a front view of the integrated light and visor control from FIG. 1;

FIG. 5 is a bottom side perspective view of the integrated light and visor control from FIG. 1 shown attached to a car roof and windshield;

FIG. 6 is a bottom front perspective view of the integrated light and visor control from FIG. 1 shown attached to a car roof and windshield;

FIG. 7 is a bottom view of the integrated light and visor control from FIG. 1 shown attached to a car roof and windshield; and,

FIG. 8 is a bottom view of the integrated light and visor control from FIG. 1.

The broken lines shown in the drawing are for illustrative purposes only and form no part of the claimed design.
